SAILBOAT

Gary Philip Wiederhold, 3952 Garfield Ave. S.,
Minneapolis, Minn. 55408

Filed Sept. 10, 1970, Ser. No. 24,943

Term of patent 3½ years

Int. Cl. D12—06

U.S. Cl. D71—1

FIG. 1 is a perspective view of a sailboat embodying my design;

FIG. 2 is a front elevational view of same;

FIG. 3 is a rear elevational view of same;

FIG. 4 is a plan view of same; and

FIG. 5 is a side elevational view of same.

A side elevational view taken from the side opposite that shown in FIG. 5 is essentially a mirror image thereof.

The omission of the sails from FIG. 4 and the sails and upper mast and rigging from FIGS. 2 and 3 is for convenience of illustration.

I claim:

The ornamental design for a sailboat, as shown and described.
